UNITED STATES PATENT OFFICE.

CAROLUS ROBERT HENDRIK ARNTZENIUS, OF THE HAGUE, NETHERLANDS.

TELEPHONE SYSTEM FOR TOLL TRAFFIC.

1,214,258.

Specification of Letters Patent.

Patented Jan. 30, 1917.

Application filed September 19, 1913. Serial No. 790,674.

To all whom it may concern:

Be it known that I, CAROLUS ROBERT HENDRIK ARNTZENIUS, a subject of the Queen of the Netherlands, and residing at Nassau 5 Odijkstraat 29, The Hague, Netherlands, have invented a certain new and useful Telephone System for Toll Traffic, of which the following is a specification.

The invention relates to a switching system for toll telephone connections, securing in a direct and simple way the handling of the traffic in one direction only between two toll telephone exchanges in each of which the connection of the concerned subscribers' 15 lines with the switching trunks is obtained by means of an order wire service.

Of late years a great many signal systems with different circuits containing relays, lamps and the like have been adopted with 20 the object of simplifying the handling of traffic. Morse signaling has even been employed at very busy periods. However, the completing of toll connections always requires the assistance of at least two toll operators at the exchanges in question, in addition to the operators for connecting the switching trunks with the subscribers' lines.

It is very desirable where the question of a ready and economical handling of the 30 traffic between two busy toll exchanges is concerned not to load the lines between the exchanges with calls in both directions, but to separate the traffic into two groups one for each direction.

The object of this invention is to provide 35 a telephone system which will permit the completion of the toll connections for each direction by the assistance of only one toll operator (the calling) and two switching operators (one at the calling and the other at the called local exchange) the calling operator controlling the traffic—*i. e.* making the necessary connections for the calls demanded at her exchange, and being relieved 45 or assisted by a suitable automatical time recording device.

According to the present invention the calling toll operator on throwing over an order wire key at her position, connects at 50 once the toll line through the distant toll exchange with an idle order wire to the switching operator of the called local exchange, so that the assistance of a toll operator at the called exchange is not necessary.

The switching over of a given order wire 55 key at the calling toll exchange causes the energizing of a relay winding at the called exchange and this permits a current to flow through a switching relay, attracting its armature in cases when at the called exchange 60 the given order wire is not occupied. This arrangement permits of the operator's sets at the called toll exchange also being connected with this order wire. However, the system is operated in such a way and the 65 circuits at the called exchange are so arranged that the operator at the calling exchange has the first option for the occupation of an idle order wire at the called exchange. For this purpose the calling operator holds the order wire key alluded to 70 switched over, and when the order wire is busy, hears a buzzer current; as soon as the line becomes idle, however, this current is cut off while at the same time the order 75 wire in question is connected automatically with the toll line. The toll operator at the distant toll exchange can test whether this order wire is idle or not by means of an order wire key, which indicates by a buzzer 80 circuit that either an operator at the same exchange or an operator of the calling exchange is using the wire. The operator at the called exchange cannot use said order 85 wire as long as the toll operator at the calling exchange holds her key in the operating position. It will be evident therefore that only one toll operator either at the calling or at the called exchange can be put at the same time into communication with the 90 switching operator at the called exchange.

The operator's work at the calling exchange can be still further simplified by the provision of any suitable known signaling system with double supervision as is 95 commonly used with local traffic, and of a time stamp and the operator has then only to throw down the starting key of the time-recorder and put a ticket into the correct 100 box.

The accompanying diagrammatic drawings illustrate by way of example a system arranged according to the present invention. In these drawings only so much of the ordinary telephone exchange circuits is shown 105 as is necessary for a good understanding of the invention.

To obtain a clear idea of the system the

figures should be put side by side in the following order from left to right:—3, 1, 2, 2^a, 4.

Figure 1 shows the arrangements at the toll switchboard at the calling toll exchange 5 hereinafter designated "toll exchange I." Figs. 2 and 2^a show the arrangements at the second toll exchange. Two positions for toll operators are shown at the top of this 10 figure. This exchange will be hereinafter referred to as "toll exchange II." The arrangement for the automatic through-connection of the toll lines from toll exchange I to the switching section at the local exchange belonging to the toll exchange II is 15 indicated in triplicate.

Incoming calls enter the toll exchange I through recording trunk lines not indicated on the drawing.

20 The local exchanges belonging to the toll exchanges I and II are named "local exchanges I_o and II_o." (Figs. 3 and 4.) The positions of the toll operators at the toll exchange II are indicated at Ft₁ and Ft₂.

25 Assume that, for instance, a subscriber 200 of the local exchange I_o desires to be connected with the subscriber 400 of the local exchange II_o. In the usual manner by means of an order wire system the subscriber's line 200 is connected with a switching trunk L₁ and multiple jack m, into which the operator at the exchange I inserts a plug St₂. The clearing lamp l^c acts as a 30 supervisory lamp for the subscriber 200, for upon his hanging up his receiver the lamp l^c is lighted and the removal of the receiver from the hook extinguishes this lamp.

In order to connect the subscriber 200 (local exchange I_o) with the subscriber 400 (local exchange II_o) the toll operator I 40 throws a key S₂ to the right. This closes:

Circuit (1).—Negative terminal 1 of a battery, winding i of the induction coil, contact 2, toll line 3, 4, connecting point 5, back 45 contact 6, windings of a relay a₂, back contact 7, connecting point 8, toll line 9, 10, contact 11, conductor 12, earth.

The relay a₂ is energized and attracts its armature. This closes:

50 *Circuit (2).*—Negative terminal 13 of a battery, resistance A₂, 14, windings of a switching relay b₂, 15, working contact 16 of relay a₂, earth; and

Circuit (3) (of the buzzer).—Buzzer, 17, 55 working contact 18 of relay a₂, back contact 19 of relay b₂, if this relay is not energized (see below), 5, 4, 3, 2, i, l, battery, earth, 12, contact 11, 10, 9, 8, back contact 20, working contact 21, 22, buzzer.

60 The relay b₂ is not energized when a toll operator at the position Ft₁ or Ft₂ has switched over her key 2, thereby closing either

Circuit (4).—Negative terminal 13 of a 65 battery A₂, 23, windings of a switching re-

lay B₂, 24, contact 25 of the key 2 of the Ft₁ operator, 26, earth, or

Circuit (5).—Negative terminal 13 of a battery A₂, 27, switching relay C₂, 28, contact 29 of the key 2 of the Ft₂ operator, 30, 70 earth.

The current passing through the switching relay b₂ is then not sufficient to have this relay attract its armatures. As long as this relay is not energized current from the 75 buzzer flows through the toll line I₂. The operator at the toll exchange I hears by means of the induction coil i that the second order wire D₂ is still occupied by an A operator in the toll exchange II (see circuit 3). 80 When, however, neither of the keys 2 of the Ft₁ or Ft₂ operators at the toll exchange II are switched over, the switching relay b₂ attracts its armature and the toll line I₂ is put in communication with the order wire D₂, 85 whereby the following circuit is closed:

Circuit (6).—Negative terminal 1 of a battery 2, 3, 4, 5, working contact 64 of relay b₂, 34, 33, receiver 68 of the switching operator at the local exchange II_o, secondary winding 67, condenser 66, 32, 31, working contact 65 of b₂, 8, 9, 10, 11, 12, earth. The buzzer circuit (3) is broken at 19 and 20 and the operator in the toll exchange I learns from this that the operator 95 of the local exchange II_o has been put in communication with the toll line I₂.

The operator at the toll exchange I asks the operator at the local exchange II_o through the toll line I₂ and the order wire 100 D₂ directly for the subscriber 400, and listens for a moment to ascertain whether the line 105 of the subscriber 400 is already occupied with another toll connection. This not being the case, she restores the key S₂ to its normal position. When the key S₂ has returned to its normal position, the circuit (1) is broken and relay a₂ becomes deenergized, which in turn, breaks the circuit of relay b₂. By means of the plug St II₂ the toll line I₂ 110 is now connected on the switching section of the local exchange II_o with the subscriber's line 400. This subscriber has been called but has not yet answered. The lines H₁ and H₂ are in communication with the receiver-circuits of the respective toll operators. 115

In the toll exchange I the lines I₁ and I₃ run to keys S₁, S₃, (not indicated in the drawing) which are of similar construction to the key S₂.

The receiver of the subscriber 400 not being removed from the hook, the relay i₂ at the local exchange II_o is energized by a current flowing from the negative terminal of a battery through the windings of a relay k 125 to earth. The third conductor 35 of the plug will thus be at negative potential and the following circuits are closed:

Circuit 7.—Negative terminal of a battery, working contact 69 of the relay i₂, 35, 130

36, back contact 37 of a relay a_2 , windings of a relay c_2 , back contact 38 of a relay e_2 , earth.

The relay c_2 attracts its armatures and 5 closes:

Circuit 8.—Negative terminal 39 of a battery, windings d_2 , working contact 40 of c_2 , 8, 9, 10, contact 41 of the key S_2 , 42, relay winding f_2 , 43, contact 44 of the key S_2 , 3, 10 4, 5, working contact 45 of c_2 , earth.

The relay f_2 attracts its armatures and the clearing lamp l_i lights. It takes some time before the slow-acting relay d_2 , attracts its armatures. At the moment that this happens, the lamp l_i extinguishes, for the circuit of the relays c_2 and f_2 is broken and the holding coil of the relay f_2 is at that moment not in communication with the negative terminal of a battery.

Circuit 9.—Negative terminal of a battery, working contact 69 of the relay i_2 , 35, 36, 37, 46, working contact 47 of e_2 , winding e_2 , 48, earth.

As soon as the subscriber 400 removes his 25 receiver from the hook, a relay l at the local exchange II_0 attracts its armature and the third conductor of the plug $St II_2$ is put directly at negative potential through the armatures and the working contacts of the 30 relays l and k .

Circuit 9a.—Negative terminal of a battery, 70, windings n , 71, working contact 72 of the hook, transmitter 73 of the subscriber 400, winding 74 of the induction coil, 75, 35 winding 1, earth.

The relay i_2 is thus short-circuited and the contact 69 opened. This deenergizes the relay e_2 and its armature falls back. The subscriber 200 speaks with the subscriber 400 40 and at the beginning of the conversation the operator of the toll exchange I pushes a key 68, by which a clock 59 is put into operation, and inserts a ticket 60 into the box 61 of a time-stamp 62 for the automatic recording 45 of the duration of the conversation. (See Fig. 1).

At the finish of the conversation the two subscribers 200 and 400 hang up their receivers. As indicated below this energizes 50 the relays g_2 and f_2 . A battery is connected with 56 when the subscriber 200 hangs up his receiver, and the relay o_2 is energized by a current flowing through the windings of the relay p , because the windings r and g , 55 the call relay of subscriber 200, get no current. their energizing circuit, negative terminal of a battery, r , subscriber's line, set 200, subscriber's line, g , earth, being broken.

Circuit 10.—Negative terminal of a battery, working contact 76 of the relay o_2 , 56, contact 57 of the plug St_2 , windings g_2 , 58, earth.

The circuit for the relay f_2 , is the same as the circuit 8, because on hanging up the receiver by the subscriber 400 the relay i_2 at

the local exchange II_0 and the relay c_2 at the toll exchange II are energized again. The key S_2 not being switched over, the holding coil of this relay also gets current thus:

Circuit 11.—Negative terminal 49 of a battery, contact 50, holding coil of relay f_2 , contact 51, 52, earth. 70

The lamps l_c and l_i light and the time stamp records automatically the duration of the conversation by the closure of:

Circuit 12.—Negative side of the battery 53, winding h_2 , contacts 54, 55, earth.

After the ticket is stamped, the clockwork 59 stops and the stamp returns to its normal or zero position. This time check is not an 80 indispensable part and does not form part of the invention proper. The plug St_2 is now pulled out from the jack m and the various lines and circuits are clear for a new connection.

Pilot lamps l_0 may be installed (as indicated on the drawing by dotted lines) in order to avoid disturbing the order wire service when an operator Ft of the toll exchange II pushes an order wire key 1, 2 or 3 90 permanently. In the order wire service the pilot lamps may therefore only flicker.

For a clear understanding of the operation of the relays B or C the following is to be noticed: When the toll operator at the 95 position Ft_1 switches over her order wire key 2, if no other toll operator at the toll exchange II or I keeps the order wire D_2 occupied, her receiver H_1 is cut-off from the talking circuit of her switchboard and connected with the order wire D_2 . 100

Circuit 12a.—Receiver H_1 , back contact 77 of the order wire key 3, working contact 78 of the order wire key 2, conductor 79, working contact 80 of the relay B_2 , connecting 105 point 81, conductor 32 of the order wire D_2 , condenser 66, secondary winding 67 of the induction coil, receiver 68, conductor 33 of the order wire D_2 connecting point 82, working contact 83 of the relay B_2 , conductor 84, 110 working contact 85 of the order wire key 2, back contact 86 of the order wire key 3, receiver H_1 .

Should a toll operator of another position, for instance at Ft_2 , depress the order wire 115 key 2 while at the position Ft_1 in the toll exchange II this order wire key is still depressed or S_2 at the calling toll exchange I is switched over, said operator will hear a 120 buzzer tone announcing that the order wire D_2 is occupied.

Circuit 12b.—Receiver H_2 , back contact 87 of the order wire key 3, working contact 88 of the order wire key 2, conductor 89, back contact 90 of the relay C_2 , buzzer, back contact 91 of the relay C_2 , conductor 92, working contact 93 of the order wire key 2, back contact 94 of the order wire key 3, receiver H_2 . 125

The relay B_2 (as per circuit 4) or the 130

4

relay b_2 (as per circuit 2) being energized, the drop in voltage in A_2 prevents the relay C_2 getting sufficient current for an attraction of its armatures (as in circuit 5). The same is the case with the relay b_2 , when the relay B_2 or the relay C_2 is energized. If several operators work at the toll exchange II, the relays b_1 , b_2 , b_3 , B_1 , B_2 , B_3 and C_1 , C_2 , C_3 and so on should be made holding relays in order to prevent the falling back of the armature of an energized relay, owing to a decrease of current therein when other shunt circuits arranged between the same battery and earth through other relays are closed. This can be attained by providing the relays with a special armature which when attracted short circuits part of the winding and decreases the resistance of the relay. (Indicated on the drawing with a dotted line).

20 It will be understood that in its application the present invention is not limited to the particular telephone system described hereinbefore by way of example. It is, e.g., not necessary that between the toll exchange and the appertaining switching section on the local exchange there are three wire connections provided as in the example; if double wire connections are provided the invention may just as well be applied.

25 Those skilled in the art will appreciate that the present invention may also be made applicable to switching systems in which there is more than one local exchange associated with the called toll exchange as has been assumed in the example. In such case any of the well-known selecting means as generally employed in semi- and full automatic telephone systems, such as, e.g., step by step mechanisms, may be used for directing the call to the right local exchange.

30 It will be easily understood that when instead of a direct connection between a subscriber of a local exchange associated with a toll exchange and a subscriber of a local exchange associated with a second toll exchange a through-connection via said second toll exchange to a third toll exchange is to be established, this may be effected with 35 the switching system according to this invention by connecting with the toll line not the B-switching operator at the local exchange associated with said second toll exchange but temporarily an idle A-operator at said second toll exchange; it will thus be possible to establish through-connections over lines connected according to this invention.

Having now described my invention what 40 I claim as new and desire to secure by Letters Patent is:—

1. In a telephone system for handling toll traffic in one direction; a plurality of stations and exchanges; means for connecting 45 a calling station and a toll exchange; and

means whereby the operator at said toll exchange can connect the toll line directly with an idle order wire between a distant toll exchange and a switching operator of a local exchange associated with 70 said distant toll exchange.

2. In a telephone system for handling toll traffic in one direction; a plurality of stations and exchanges; means for connecting a calling station and a toll exchange; a 75 switching key at said toll exchange; a relay at a distant toll exchange; means whereby said switching key operates said relay; a distant local exchange; an order wire between said local exchange and the distant 80 toll exchange; and means whereby said relay connects the operator at the calling toll exchange to said order wire and thus to the switching operator of said distant local or called exchange.

3. In a telephone system for handling toll traffic in one direction; a plurality of stations and exchanges; means for connecting a calling station and a toll exchange; a switching key at said toll exchange; a relay 90 at a distant toll exchange; a distant local exchange; an order wire between said local exchange and the distant toll exchange; a buzzer at the distant toll exchange and means whereby the switching key operates 95 the relay to connect the buzzer across the toll operator's toll lines when said order wire is engaged.

4. In a telephone system for handling toll traffic in one direction; a plurality of stations and exchanges; means for connecting a calling station and a toll exchange; a switching key at said toll exchange; a relay at a distant toll exchange; means whereby said key operates said relay; a 100 second switching relay and a battery at the distant toll exchange; means whereby the first relay operated from the calling toll exchange completes a circuit from the battery through said second relay to earth; 110 a distant local exchange, an order wire between said local exchange and the distant toll exchange; a plurality of corresponding order wire keys, one for each operator at the distant toll exchange; means 115 whereby any one of said order wire keys, when engaging the order wire in question, completes a circuit from said battery to earth, means whereby said second switching relay on the completing of its circuit 120 connects the calling toll operator directly to the order wire and thence to the distant local exchange should a circuit from said battery to earth not be closed through one of said order wire keys; a buzzer circuit at 125 the distant toll exchange and means whereby said buzzer circuit is connected across the calling toll operator's lines should the circuit from said battery to earth be closed through one of said order wire keys.

130

5. In a telephone system for handling toll traffic in one direction; a plurality of stations and exchanges; means for connecting a calling station through a local exchange to a toll exchange; means whereby the operator at said toll exchange can connect a toll line directly to an idle order wire at a distant toll exchange and thence to the switching operator of the called local exchange and means whereby a buzzer circuit warns any operator at the distant toll exchange who attempts to engage the order wire already engaged by the calling toll exchange.
- 10 6. In a telephone system for handling toll traffic in one direction; a plurality of stations and exchanges; means for connecting a calling station through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire between the distant toll exchange and a distant local exchange; means whereby the effective energization of said second switching relay connects the calling toll operator to the order wire; a plurality of order wire keys at the distant toll exchange; a switching relay associated with each of the order wire keys, each adapted to connect an operator at said distant toll exchange to the order wire; a circuit from said battery to earth through each of these switching relays, the circuit being closed when the associated order wire key is operated in the attempt to engage the order wire; an armature for each of the relays which is connected in shunt between said battery and earth; means whereby said armature when attracted short circuits part of its relay winding thus decreasing the resistance of the relay and preventing the return of the armature when other shunt circuits are closed; means whereby any one circuit from said battery to earth being closed, that is to say, the order wire being engaged, the shunt current available for any other of the relay circuits between the battery and earth is insufficient to effectively energize the relay in said circuit; a buzzer circuit in association with each of the relays connected between the battery and earth; and means whereby said buzzer circuit is connected across an operator's receiver when such operator closes a circuit from the battery to earth through a relay and the relay is not effectively energized.
- 15 7. In a telephone system for handling toll traffic in one direction; a plurality of stations and exchanges; means for connecting a calling subscriber through a local exchange to a toll exchange; means whereby the operator at said toll exchange can connect the toll line directly with an idle order wire between a distant toll exchange and a switching operator of a local exchange associated with said distant toll exchange; a switching trunk whereby this switching operator can connect the called subscriber to the toll line; a lamp at the calling toll exchange; means whereby said lamp lights when the called subscriber is to be disconnected from the toll line and has hung his receiver on the hook.
- 20 8. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire
- 25 between the distant toll exchange and a distant local exchange; means whereby the effective energization of said second switching relay connects the calling toll operator to the order wire; a plurality of order wire keys at the distant toll exchange; a switching relay associated with each of the order wire keys, each adapted to connect an operator at said distant toll exchange to the order wire; a circuit from said battery to earth through each of these switching relays, the circuit being closed when the associated order wire key is operated in the attempt to engage the order wire; an armature for each of the relays which is connected in shunt between said battery and earth; means whereby said armature when attracted short circuits part of its relay winding thus decreasing the resistance of the relay and preventing the return of the armature when other shunt circuits are closed; means whereby any one circuit from said battery to earth being closed, that is to say, the order wire being engaged, the shunt current available for any other of the relay circuits between the battery and earth is insufficient to effectively energize the relay in said circuit; a buzzer circuit in association with each of the relays connected between the battery and earth; and means whereby said buzzer circuit is connected across an operator's receiver when such operator closes a circuit from the battery to earth through a relay and the relay is not effectively energized.
- 30 9. In a telephone system for handling toll traffic in one direction; a plurality of stations and exchanges; means for connecting a calling subscriber through a local exchange to a toll exchange; means whereby the operator at said toll exchange can connect the toll line directly with an idle order wire between a distant toll exchange and a switching operator of a local exchange associated with said distant toll exchange; a switching trunk whereby this switching operator can connect the called subscriber to the toll line; a lamp at the calling toll exchange; means whereby said lamp lights when the called subscriber is to be disconnected from the toll line and has hung his receiver on the hook.
- 35 10. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire
- 40 11. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire
- 45 12. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire
- 50 13. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire
- 55 14. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire
- 60 15. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire
- 65 16. In a telephone system for handling toll traffic in one direction; a plurality of stations and exchanges; means for connecting a calling subscriber through a local exchange to a toll exchange; a switching key at the toll exchange; a relay at a distant toll exchange, said relay being adapted to be operated by the switching key at the first toll exchange; a battery and a second switching relay at the distant toll exchange; means whereby a circuit from the battery to earth is closed through the second switching relay when the first relay is actuated; an order wire

the switching operator at the distant local exchange can connect the called subscriber to a toll line; a further line between the distant toll exchange and the distant local exchange; a relay (c_2) at the distant toll exchange; means whereby, when the called subscriber is connected to the toll lines, when the receiver of the called subscriber is on its hook and when the switching key at 5 the calling toll exchange is in its rest position so that the relay at the distant toll exchange which is adapted to be operated by said key is not energized, a circuit is closed through and energizes said relay (c_2); a 10 slowing-acting relay (d_2, e_2) at the distant toll exchange; a separate holding winding on said slow-acting relay; a relay (f_2) and a lamp at the calling toll exchange; means whereby a circuit between a battery and 15 earth is closed through said lamp when the relay (f_2) is energized; means whereby the 20

energization of the relay (c_2) closes a circuit through the slow-acting relay, a toll line between the distant toll exchange and the calling toll exchange, the switching key 25 at the calling toll exchange, provided said key is in its said rest position, and the relay (f_2) which is energized so that the lamp associated with it lights up; means whereby the slow-acting relay eventually breaks the 30 circuit through the relay (c_2) and therefore the circuit through the relay (f_2), and closes a circuit through the holding winding provided on itself and the said further line between the distant toll exchange and the distant local exchange, this last circuit being maintained until the called subscriber's receiver is lifted from its hook. 35

In testimony whereof I have signed my name to this specification.

CAROLUS ROBERT HENDRIK ARNTZENIUS.

Copies of this patent may be obtained for five cents each, by addressing the "Commissioner of Patents, Washington, D. C."
